Fig. 2

Fig. 3

Fig. 4

FIGURE 1 is a front perspective view of the front of a night depository showing my new design;

FIGURE 2 is an elevational view taken from one side thereof, the opposite side being a mirror image of the side shown;

FIGURE 3 is a top plan view thereof, the bottom being a mirror image of the top shown;

FIGURE 4 is a rear elevational view thereof; and

FIGURE 5 is a front perspective view of a modified form of the front of a night depository shown in FIGURE 1, the sides, top, and bottom being the same as those shown in FIGURES 2 through 4.

The dominant features of my design reside in the portions shown in full lines, it being understood that the

broken line showing of the depository in the figures is for purposes of illustration only.

I claim:

The ornamental design for the front of a night depository, substantially as shown and described.
